G. Warren Brown. John Logan

United States Patent Office.

JOHN LOGAN, OF BOSTON, MASSACHUSETTS.

Letters Patent No. 105,467, dated July 19, 1870.

IMPROVEMENT IN HAIR-SPRING-TESTING APPARATUS FOR WATCHES.

The Schedule referred to in these Letters Patent and making part of the same

To all whom it may concern:

Be it known that I, JOHN LOGAN, of Boston, in the county of Suffolk and State of Massachusetts, have invented Apparatus for Ascertaining the Length of Hair-Springs; and I do hereby declare that the following, when taken in connection with the drawing which accompanies and forms a part of this specification, is a description of my invention sufficient to enable those skilled in the art to practice it.

In watch-making, much time has to be expended in the adjustment of the hair-springs, the length of which determines the duration of the oscillations of the balance-wheel.

Heretofore, the length of hair-springs has been determined by actual trial of them in the watches of which they form a part, which is a tedious, and, therefore, expensive operation, great care having to be exercised, and there being no special conveniences or appliances in watches for confining the spring at considerably varying lengths, or for readily entering to or taking from its place a balance-wheel with its attached hair-spring.

My invention consists in an apparatus provided with means for readily introducing a balance-wheel and its attached hair-spring to a time-keeping train, actuated by a mainspring, and for readily removing the same therefrom, and with means for clamping the free end of the hair-spring at any reasonable distance along its length; also, in such an apparatus, combining with the mainspring a supplemental spring, so that, by adjustment of the latter, an additional impelling force can be brought readily to act upon the hair-spring to be adjusted, and so that said force can be as readily removed; and also in the arrangement with said train and the index which shows its rate of movement, of another regulated time-keeping train having an index, so that, by comparing the rate of movement of the train having the hair-spring, the length of which is to be adjusted, with the rate of movement of the regulated train, the operator can see at a glance whether the hair-spring to be adjusted as to length has its free end so clamped that the operative part of the spring is too long, too short, or just right.

Figure 1 of the drawing shows my apparatus partly in side elevation and partly in vertical section, and

Figure 2 shows the same in plan.

In this apparatus there is nothing novel about the time-keeping trains, *per se*; any pair of good similar trains may be used, in each of which the power of a mainspring is brought to an escapement, operative upon a balance-wheel provided with a hair-spring; therefore, in this description, reference to the general and well-known construction and operation of such trains will be omitted.

Two suitable spring-impelled time-keeping trains are arranged in one frame common to both, that on the left of fig. 2 being provided with a regulated balance-wheel and hair-spring, so as to move at the standard rate, and carrying an index-hand, *a*.

The right-hand side of the apparatus is arranged for testing the hair-springs to be adjusted as to length, this being the most convenient for the operator.

The balance-wheel bridge *b* of the right-hand train is removably fixed in position by two steady-pins, *c c*, and the swinging spring clamp *d*, so that the bridge *b* can be easily removed to enter a balance-wheel and to remove it.

Said bridge is provided with an adjustable screw, *e*, in which is the upper pivot-bearing for the balance-wheel, and in the frame, in line with said screw, is another similar screw, *e'*, so that, by adjustment of both or either of said screws, the balance-wheel may be properly set.

On the left of the bridge *b* is arranged a clamping apparatus, suited to receive the free end of the hair-spring *f*.

Said apparatus consists of a cam or eccentric, which can be turned by lever *g*, so as to clamp the hair-spring between said cam and a projection from the piece *h*, which holds the cam.

When a balance is placed in position between the screws *e* and *e'*, the lever *g* is so placed as to leave an opening between its cam and the projection from piece *h*, and the free end of the hair-spring is introduced into said opening. The said end is left exceeding the maximum length required, and is drawn between the said cam and projection as far as the operator may deem necessary, and, by movement of lever *g*, is clamped there.

The right-hand train is then allowed to vibrate the balance-wheel, and the operator observes the rate of movement of the index-hand *i* with reference to the index-hand *a*; both moving in the same direction, so that it is easily seen, if they move isochronously, or whether hand *i* gains or loses with reference to hand *a*. If the former, then the free end of the spring *f* is unclamped, and is drawn back and again clamped, and the rate of movement observed. If the latter, the spring is unclamped, its free end drawn further through beyond the cam, and again clamped, and the rate of movement observed.

As the degree of stress of the mainspring operates to increase or diminish the degree of vibration of the balance-wheel, I have added to the mainspring of the experimental train a supplemental spring, *j*, fixed to the arbor *k* of the mainspring.

The end of spring *j* is formed as a hook, and pins, *l*, are set around spring *j*, in the frame of the apparatus,

so that, by the aid of a knob, m , fixed on spring m' , it can be coiled to any desired degree of tension required, and retained at such tension by coupling the hook upon any one of the pins l , as may be desired.

When, after suitable adjustments of the hair-spring f , and observations of the rate of movement indicated by the index hand i , under light and strong stress exerted from the main spring and its supplement, the movements of both trains are found to be practically isochronous; then the operator breaks off the end of the hair-spring projecting beyond the point where it is clamped, which brings the length of the spring such that it is ready to be placed in the watch to which it belongs, when no further adjustment as to length will be needed, except that which is within the range of the movement of the regulator, with which the watch is provided.

If desired, a minute-hand, n , may be added to the regulated train, so that the rate of gain or loss of i , with reference to a , may be observed conveniently for any number of minutes.

The operator, on commencing his observation of comparison, can readily, with any small instrument, check or accelerate the movement of one of the hands a or i , so that, at a given moment, they will start from corresponding positions, and then the gain or loss of movement of the hand i over the hand a will be readily seen.

The indicating-hands a and i , I place on the fifth-wheel arbors, which wheels are the escapement-wheels,

so that each movement of the said hands indicates one-fifth of a second, instead of placing the indicating-hands on the arbors of the fourth-wheels, where they would, by each movement, indicate seconds; and thus I am enabled more quickly and readily to detect any variation in the rate of movement of the two indicating-hands.

I claim—

An apparatus for determining the proper length of hair-springs for watches, the same consisting of two independent time-keeping spring-driven trains, one of which is adjusted to run at the standard rate, and the other of which has provision for easily and temporarily connecting with it balance-wheels with attached hair-springs, the lengths of which are to be determined, the two trains having each rapidly-moving indicating-hands designed to move isochronously, and exposed, so that they may be turned and set to the same starting point.

Also, in combination with the main driving-spring arbor k , the supplemental spring j , arranged substantially as and for the purpose specified.

3. Also, the arrangement, with the removable bridge b and the plate on which it rests, of adjustable screws in the same axial line, and provided with bearings or steps for the balance-wheel arbor.

JOHN LOGAN.
